UNITED STATES PATENT OFFICE.

KARL H. HANSEN, OF PITTSBURGH, PENNSYLVANIA, ASSIGNOR TO ORENSTEIN-
ARTHUR KOPPEL CO., OF KOPPEL, PENNSYLVANIA, A CORPORATION OF PENN-
SYLVANIA.

RAIL-FASTENER.

1,250,117.

Specification of Letters Patent. Patented Dec. 11, 1917.

Application filed April 17, 1915. Serial No. 22,172.

To all whom it may concern:

Be it known that I, KARL H. HANSEN, a citizen of the United States, and resident of Pittsburgh, in the county of Allegheny and State of Pennsylvania, have invented a new and useful Improvement in Rail-Fasteners; and I do hereby declare the following to be a full, clear, and exact description thereof.

My invention relates to rail fasteners and 10 more particularly to the kind employed in connection with portable railway tracks.

Portable railway tracks are usually made in sections, which sections are either made up and when transported to the place of use, 15 are merely laid on the ground and coupled together, when the railroad is ready for traffic; or, the rails, ties, etc., may be shipped and assembled on the ground. The rails are laid on steel ties, and my invention relates to the device for fastening the rails to 20 the ties, its object being to provide a fastener, which will hold the rails securely in position and prevent the rails from tilting due to the pressure of the wheels. A further 25 object of my invention is to provide a device in which the rail is held securely in position without having the fastening devices pass through openings cut into the ties and which tend to weaken the construction.

To these ends, my invention comprises the 30 novel features hereinafter set forth and claimed.

In the accompanying drawings, Figure 1 is a plan view of a portion of a tie and rail 35 showing my improved fastener; Fig. 2 is a section on the line 2—2, Fig. 1; and Fig. 3 is a section on the line 3—3, Fig. 2.

The numeral 2 designates the rail having the flanges 3, which rest upon the tie 4. 40 The tie 4 is a channel-shaped member with the depression or groove 5 rolled or otherwise formed therein longitudinally thereof.

The fastener comprises the clutch-bolt 6, which has the inturned end portion 7, the 45 straight shank portion 8, and the threaded end portion 9. The inturned portion 7 and the shank 8 are preferably formed oblong in cross-section, the upper face of the shank being preferably formed flat. The end portion 9 is preferably upwardly inclined for 50 the purpose more fully hereinafter set forth.

The inwardly turned end portion 7 of the clutch-bolt engages the flange of the rail on one side, the shank portion 8 passes under 55 the rail in the depression 5 of the tie, and

the upwardly inclined end portion 9 passes through the opening 10 formed in the plate or abutment 10^a of the clip 11. The clip 11 is secured by the rivets 12, or in any other suitable manner, to the tie 4, the lip 13 extending over the adjacent flange of the rail. The clip 11 is formed with the projection 14, which extends below the bottom face of the rail base, and the shank of the clutch-bolt in passing beneath said rail, engages said 60 projection 14.

The clip 11 is provided with the swell 15 to accommodate the upwardly extending portion 9 of the clutch-bolt, and said swell has the plate or abutment 10^a in which the 70 opening 10 is formed, through which the upwardly extending inclined portion 9 of the clutch-bolt passes, said abutment being slightly outwardly inclined.

A nut 16 engages the threaded portion 17 75 of the upwardly inclined portion 9 of the clutch-bolt, and when said nut is drawn up tight against the abutment 10^a, the inner end 7 of the clutch-bolt is forced into contact with the flange of the rail, and the opposite flange is forced into close engagement with the lip 13 of the clip 11. By having the projection 14 on the clip 11 extending below the rail base and engaged by the shank of the bolt, when the nut 16 is tightened 80 up and the inner end 7 of the clutch-bolt is forced into contact with the flange of the rail, the clutch-bolt is drawn up tight against the projection 14 and is held in a horizontal position so that it cannot lift up. 85 If it were not for this contact between the clip and the clutch-bolt, the rail would be liable to lift away from the tie to some extent if the track sections were lifted by the rails. The clip 11 is made of a steel or other 90 metal having a suitable amount of resiliency, so that the plate or abutment when engaged by the nut 16 for drawing up the clutch bolt can yield so as to make a tighter hold and at the same time acts as a lock for 95 the nut.

I prefer to arrange the clip 11 on the inside of the rail for the reason that the pressure on the rail due to the locomotive and cars tends to tilt the rail outwardly, and 100 the clip when placed on the outside, is not so efficient to prevent this.

By my improved fastener, the clips may be riveted on to the ties and the clutch-bolt inserted loosely so that to assemble the 110

tracks, the rails only need to be laid down on the ties with one edge inserted under the clip, and the nut on the clutch-bolt is then tightened up by a few turns of a wrench. 5 In this way, by having the parts all attached to the tie, the rapidity with which the track sections may be formed is greatly increased; and, at the same time, the parts are not liable to become lost or mislaid.

10 What I claim is:

1. In a rail fastener, the combination of a tie having a longitudinal groove therein, a clip secured to said tie having a flange engaging lip, a projection on said clip extending below the rail base, an outwardly inclined abutment extending down into said groove and having an opening therein, a bolt having an inwardly extending end portion, a shank portion passing through said groove engaging said projection, an upwardly inclined end portion passing through

said opening in said abutment, and a nut engaging said upwardly inclined end portion beyond said abutment.

2. In a rail fastener, the combination of 25 a tie having a longitudinal groove therein, a clip secured to said tie having a flange engaging lip and outwardly inclined resilient abutment on said clip having an opening therein, a bolt having an inwardly extending 30 end portion, a shank portion passing through said groove, an upwardly inclined end portion passing through said opening in said abutment, and a nut engaging said outwardly inclined abutment. 35

In testimony whereof, I, the said KARL H. HANSEN, have hereunto set my hand.

KARL H. HANSEN.
